US00D868697S

(12) **United States Design Patent**
Tanizaki

(10) **Patent No.:** US D868,697 S
(45) **Date of Patent:** ** Dec. 3, 2019

(54) **TERMINAL METAL FITTING FOR
ELECTRICAL CONNECTOR**

(71) Applicant: **SUMITOMO WIRING SYSTEMS,
LTD.**, Mie-ken (JP)

(72) Inventor: **Toshifumi Tanizaki**, Yokkaichi (JP)

(73) Assignee: **SUMITOMO WIRING SYSTEMS,
LTD**, Mie-Ken (JP)

(**) Term: **15 Years**

(21) Appl. No.: **29/666,840**

(22) Filed: **Oct. 16, 2018**

(30) **Foreign Application Priority Data**

Apr. 20, 2018 (JP) 2018-008774

(51) **LOC (12) Cl.** 13-03

(52) **U.S. Cl.**

USPC D13/133

(57) **CLAIM**

The ornamental design for a terminal metal fitting for electrical connector, as shown and described.

DESCRIPTION

FIG. 1 is a front, top and right side perspective view of a terminal metal fitting for electrical connector showing my new design;

FIG. 2 is a rear, bottom, and left side perspective view thereof;

FIG. 3 is a front view thereof, the rear view being a mirror image of FIG. 3;

FIG. 4 is a top plan view thereof;

FIG. 5 is a bottom plan view thereof;

FIG. 6 is a right side view thereof; and,

FIG. 7 is a left side view thereof.

1 Claim, 6 Drawing Sheets
